ELECTRON DISCHARGE DEVICE

Bernard Salzberg, East Orange, N. J., assignor,
by mesne assignments, to Radio Corporation of
America, New York, N. Y., a corporation of
Delaware

Application March 6, 1935, Serial No. 9,543

4 Claims. (Cl. 250—27.5)

My invention relates to electron discharge devices, more particularly to electron discharge devices for use at ultra-high frequencies.

The maximum frequency at which the conventional tube will operate is limited principally by interelectrode and interlead capacity and by the inductance of the leads to the electrodes because the inductance and capacity of the electrodes and leads form an electric system which determines the upper limit of frequency at which the tube will operate. While the interelectrode capacity may be decreased and the upper frequency limit at which a tube will operate increased by making electrodes small, making them short and bringing out the leads at different points of the bulb, such a tube is difficult and expensive to make because of special constructions and methods required for assembling such tubes. Where the electron discharge device is of the multi-grid type, it becomes difficult to provide proper shielding between the various elements in the tube, particularly between the control grid lead and the anode. Shielding becomes important at the very high frequencies at which the tubes are intended to operate.

An object of my invention is to provide an electron discharge device which may be made commercially even in very small sizes and in which the interlead capacity and the inductance of the leads are considerably less than in the conventional type. Another object of my invention is to provide an electron discharge device of the type described in which the overall dimensions and interelectrode spacing is much less than is feasible with tubes constructed in the usual way. A still further object of my invention is to provide an electron discharge device of the type described in which the various elements and leads are properly shielded from one another.

The novel features which I believe to be characteristic of my invention are set forth with particularity in the appended claims, but the invention itself will best be understood by reference to the following description taken in connection with the accompanying drawing in which Figure 1 is a perspective view with parts broken away of the electrode mount assembly of an electron discharge device embodying my invention; Figure 2 is a vertical section of the electrode mount assembly shown in Figure 1; Figure 3 is a bottom plan view of the electrode mount assembly shown in Figure 2; and Figure 4 shows an electron discharge device made in accordance with my invention and mounted in a shielded type of socket.

The envelope 10 of the tube shown in Figure 4 encloses and supports a unitary electrode mount assembly shown in detail in Figures 1 to 3 inclusive and comprising an indirectly heated cathode 11, a control grid 12, a screen grid 13, suppressor grid 14 and an anode 15, which may

be a box-like structure made from sheet metal. The anode 15 is provided with a pair of flat side rods 16 which could be made integral with the plate and which have shoulders 17 for supporting electrode spacers 18 and 19 of insulation such as mica and preferably in the form of plates or discs transverse to the longitudinal axis of the electrode mount. The shoulders 17 are bent over on the outside of and against the mica plate members and may lie in slots in the edges of the plate members as shown to rigidly secure the spacers to the anode so as to provide a rigid and unitary electrode assembly.

In accordance with my invention described and claimed in my copending application Serial No. 15 732,028 filed June 23, 1934 and assigned to the Radio Corporation of America, radially positioned stiff conductors 20, which serve as lead-ins and mount support wires, extend thru an annular press 21 in the wall of the envelope 10 as shown 20 in Figure 4 and have secured to their inner ends, preferably by welding, U-shaped conductors 22 having one end threaded thru apertures 23 in the insulating disc or plate 19 to secure the conductors 20 to the plate member as best shown in 25 Figure 1, one end 24 of conductor 22 being formed to engage the bottom of the insulating plate 19 and the other end 25 being electrically connected to one of the electrodes mounted between the 30 plates 18 and 19. The outer ends of the conductors 20 serve as tube contacts, as best shown in Figure 4, to be received in a properly designed socket. This construction eliminates the need of the usual reentrant stem press and materially 35 reduces the overall dimensions of the tube. It will be observed that the control grid lead 26, and the anode lead 27, are positioned to extend from opposite ends of the envelope to reduce interlead capacity and inductance and to separate 40 the input and output leads as much as possible. The getter tab 28 is preferably secured to the upper end of the mount. It is formed to direct the getter against the side wall of the envelope.

In accordance with my invention shielding is 45 provided to shield the anode and its lead from the control grid and its lead. This shielding includes a top disc-like metal shield 31 provided with a rectangular aperture 32, as best shown in Figure 2, thru which the end of the cathode and the grid side rods extend, and is supported in 50 spaced relationship with respect to the mica disc 18 by means of small pips 33 on the bottom of the disc. Attached to a collar 34 on the disc shield 31 is a box-like portion 35 which completely shields the end of the cathode and grid side rods from the plate lead 37. This shielding is 55 out of contact with the plate side rods. This upper shield may be secured to the mount and connected by means of a pair of side rods 36, 60 only one of which is shown, to a lower shield com-

prising an inverted cup-shaped metal member 37 provided with a rectangular aperture 38 thru which the ends of the cathode and grid side rods extend. Other apertures 39 are provided thru 5 which the ends 25 of the fastening conductors 22 extend. This lower shield is insulated from the mount by means of intermediate insulating disc 40 which registers with the insulating disc 19 and is provided with an aperture 41, thru which 10 the end of the cathode and grid side rods extend. The ends 25 of the fastening conductors extend thru the mica disc 40 and the apertures 39 to be connected to the proper electrodes. The shields may be connected by means of a strap 42 to the 15 cathode, which is usually at ground potential or may be provided with a separate lead. The upper and lower shields are, therefore, completely insulated from the electrode mount assembly and connected to the cathode, and with the screen 20 grid and suppressor grid, which may be provided with a separate lead as shown, completely shields the anode and anode lead from the control grid and control grid lead.

The electron discharge device made in accordance with my invention may be mounted in a specially designed tube socket as best shown in Figure 4. The socket may include a shielding partition 43, having a ring 44 of insulating material upon which the clip type contacts 45 may be supported to receive the terminals 20 of the electron discharge device. It will thus be seen that by means of this arrangement the input circuit which is connected to lead 26 and the output circuit which is connected to lead 27 are completely shielded from each other.

A tube constructed in accordance with the above invention may easily be made of very small dimensions, is sturdy and reduces interelectrode capacity and inductance to a very small value, 40 permitting operation of the tube at extremely high frequencies.

While I have indicated the preferred embodiment of my invention of which I am now aware and have also indicated only one specific application for which my invention may be employed, it will be apparent that my invention is by no means limited to the exact forms illustrated or the use indicated, but that many variations may be made in the particular structure used and the purpose 50 for which it is employed without departing from the scope of my invention as set forth in the appended claims.

What I claim as new is:—

1. An electron discharge device including an envelope, a unitary electrode mount assembly positioned within the envelope and comprising a pair of insulating plate members and electrodes positioned between and secured to said members, stiff lead-in conductors extending thru the wall 55 of the envelope and positioned around the periphery of one of said insulating plate members, means at the inner ends of said stiff lead-in conductors securing the conductors to said one of said insulating plate members for supporting the 60 mount within the envelope and for electrically connecting the conductors to the electrodes positioned between the insulating plate members, and electrostatic shielding members positioned 65 on opposite ends of the electrode mount assembly and secured to said insulating plate members out of contact with said electrode assembly.

2. An electron discharge device including an envelope, a unitary electrode mount assembly po-

sitioned within the envelope and comprising a pair of insulating plate members, electrodes positioned between and secured to said members and having their ends extending thru said members, stiff lead-in conductors positioned around the periphery of one of said insulating plate members and secured to said one of said insulating plate members and electrically connected to said electrodes, a cup-shaped metal shield positioned on the outside of said mount adjacent said one of said insulating plate members and provided with an aperture thru which the ends of the electrodes extend, an insulating plate member positioned between said one of said insulating plate members and said shield to electrically insulate 15 said shield from the electrodes in said mount and said stiff lead-in conductors, and means for securing said shield to said mount.

3. An electron discharge device including an envelope, a unitary electrode mount assembly positioned within the envelope and comprising a pair of insulating plate members, electrodes positioned between and secured to said members and having their ends extending thru said members, stiff-lead-in conductors positioned around the periphery of one of said insulating plate members and secured to said one of said plate members and electrically connected to said electrodes, a cup-shaped metal shield positioned at one end on the outside of said mount adjacent said one of said insulating plate members and provided with an aperture thru which one end of the electrodes extend, an insulating plate member positioned between said one of said insulating plate members and said shield to electrically insulate 30 said shield from the electrodes in said mount and said stiff lead-in conductors, a shield for the other end of said mount provided with a box-like portion into which the other ends of the electrodes extend, said shields being electrically 35 connected together and secured to said mount by rods extending longitudinally of said mount thru said insulating plate members and secured to said shields.

4. An electron discharge device including an envelope, a unitary electrode mount assembly positioned within the envelope and comprising a pair of insulating plate members, electrodes positioned between and secured to said members and having their ends extending thru said members, radially positioned stiff lead-in conductors extending thru the wall of the envelope, a second conductor secured intermediate its ends to the inner ends of said lead-in conductors, said second conductor having one end secured to one of the insulating plate members and the other end electrically connected to an electrode in said electrode mount assembly whereby said mount is supported within said tube by said radially positioned lead-in conductors, a cup shaped shielding member secured to said one of the insulating plate members and provided with an aperture thru which ends of said electrodes extend, an insulating plate member positioned between said shield and said one of said insulating plate members to electrically insulate said shield from said lead-in conductors and said second conductors and provided with apertures thru which said second conductors extend to be connected 60 to the ends of said electrodes and means for securing said shield to said mount assembly.
